UNITED STATES PATENT OFFICE.

JOSEPH GOTTLIEB, OF NEW YORK, N. Y.

DESIGN FOR A BICYCLE-FRAME.

SPECIFICATION forming part of Design No. 32,200, dated February 6, 1900.

Application filed October 23, 1899, Serial No. 734,595. Term of patent 3½ years.

To all whom it may concern:

Be it known that I, JOSEPH GOTTLIEB, a citizen of the United States, and a resident of New York city, in the county and State of New York, have invented and produced a new and original Design for Bicycle-Frames, of which the following is a specification.

As shown in the drawing, the leading and material feature of my design consists in the design of the bicycle-frame as illustrated in said drawing.

The drawing accompanying this specification represents a side view of a bicycle-frame embodying my design.

15 A represents the frame, consisting of the frame-bars B, C, D, E, F, and G and crank-hub H. Between the frame-bars E and F is

placed the supplemental hub J, which is supported in place by the short arms or bars K and L, brazed to the frame-bars E and F. 20 This supplemental hub is intended to support the axle of an auxiliary semierank mechanism.

I claim—

The design for a bicycle-frame as shown 25 and described.

Signed at New York, in the county of New York and State of New York, this 17th day of October, A. D. 1899.

JOSEPH GOTTLIEB.
